HEAT RECOVERY METHOD AND MEANS

Minor W. Stout, Kansas City, Mo.

Application March 6, 1933, Serial No. 659,729

12 Claims. (Cl. 122—396)

This invention relates to improvements in heat recovery methods and means, and more particularly to a system for the recovery of the heat content of steam and water from steam boilers, such that, following cleaning or inspection of the boiler, a substantial part of the original heat content may be restored to a fresh supply of boiler feed water. The system to be described by way of exemplifying the invention, illustrates a preferred and improved practice in the recovery of heat from locomotive boiler blowoff fluids.

As conducing to a better understanding of the advantages of the method and apparatus identified with the present system, it may be noted that the heretofore prevailing practice of washing and cleaning locomotives upon arrival there-of in a roundhouse after a run, consists, first, in blowing off the boiler water, containing a substantial amount of mineral; this water existing at a temperature of the order of 360° F., corresponding say, to 150 pounds gauge pressure. The blowoff operation usually takes place by connection of the locomotive boiler, say to a blowoff header, and thence into a blowoff tank. At usual temperature and pressure a great deal of flash steam is usually given off, connection being made from the blowoff header, according to prevailing practice, to a nozzle in the feed water storage tank, so that the resulting flash steam is utilized in some measure, to heat the boiler feed water which may be supplied from a suitable softener or from the mains. After completion of the blow-off operation, the water taken from the blowoff storage tank is cooled down with fresh water, say to a temperature of 120–130 degrees F. This water is forced as by a steam driven pump, at about 100 pounds pressure, into the mud drum of the locomotive. After the mud and scale is there loosened up and removed, the washout water is run to the sewers. Water from a clean water storage tank is then delivered to the clean locomotive boiler, at say 180 degrees temperature. The locomotive is then again ready to be fired, and after some little period of time is enabled again to proceed under its own steam. During the period of steaming up the locomotive boiler is usually washed externally with an additional amount of the blowoff water, which, however, must be cooled down with water from the mains or other source, to a temperature of 120 or 130 degrees F., so that it can be handled through a hose. The heat loss incident to this operation will be obvious, when it is considered that an initial amount, say of 3,000 gallons of water at 360° F., or 150 pounds pressure, undergoes such a

change of conditions that, at the start of the re-steaming operation, the same locomotive will contain say 3,500 gallons of fresh feed water at a temperature of not to exceed 180 degrees. The foregoing operation, while subject of course to the varying practices of different railroads, serves to typify the heat waste normally incident to the practice prevailing before the advent of the present system.

An object of the invention may thus be generally stated as the improvement of facilities for reclaiming heat from blowoff boiler fluids, resulting in a greater recovery of the heat content of boiler drainage and flash steam, than is possible through the use of the prevailing facilities for this purpose.

Another object of the invention is attained in an improved combination of blow-off storage tanks and interconnecting lines, with heat recovery devices adapted respectively for the transfer of heat from the blowoff water to the boiler feed water, and for the transfer of the heat units of blowoff steam, to a fresh water supply utilized for refilling the boiler, for example, after cleaning or inspection.

Still further objects are attained in an interconnected or functionally related aggroupment of apparatus, such that a substantial part of the boiler blowoff water and steam may be temporarily stored under a substantial pressure; in the utilization of improved heat exchanging facilities, such that a portion of the blow-off water and/or steam may be conducted in heat transferring relation to a supply of fresh make-up water; further in a combination of apparatus such that all or a portion of the flash steam from the blowoff fluid is caused to deliver a substantial part of its heat content for preheating a supply of clean boiler feed water.

Numerous other objects are attained in substantial improvements in the individual items of equipment utilized in the combination or system; among these may be mentioned an improved reservoir for receiving the incoming liquid in a heat exchanger of counterflow or zigzag type; an improved arrangement for circulating liquid within the tubes of such a heat exchanger; an improved strainer for use in connection with the pumps, or some thereof, of the present system. It is to be noted, however, that certain of the embodiments of these objects are perhaps applicable to apparatus other than the units of the present system.

The foregoing and many additional objects will appear from the following detailed description of

the items of apparatus going to make up the system, and the technique involved in their use, considered in connection with the accompanying drawings, in which:

- 5 Fig. 1 is an elevation illustrating in part diagrammatically, the different items of apparatus employed in an existing system, according to the present invention, certain items of the apparatus being illustrated in vertical sectional elevation to disclose parts internally thereof; Fig. 2 is a side elevation of a heat exchanger of a type preferably employed in connection with the system of the present invention; Fig. 3 is a vertical section along line 3—3 of Fig. 2; Fig. 4 is a horizontal section along line 4—4 of Fig. 1, being taken through a heater head or steam water heating device, as utilized according to the present invention; Fig. 5 is a section along line 5—5 of Fig. 1; Fig. 6 is a longitudinal sectional elevation of a steam ejector device employed in the present system; Fig. 7 is a plan view, and Fig. 8 is a side elevation, of a preferred form of strainer such as utilized in connection with the pump intake of portions of the system.
- 25 The invention is herein described with reference to an installation of heat-recovery and transfer means, in a railroad roundhouse, as there utilized for reclaiming heat from the drainage and blowing-off of locomotive boilers. My preference is to provide, say along the wall of the roundhouse, a plurality of headers whereby the heat recovery plant may be installed in such location as not to interfere with the trackage and other usual roundhouse equipment and floor space. There is accordingly provided a blowoff header 10, a washout header 12, and a water header 14, for boiler fillup water. Each of these headers is in the nature of a manifold, which may be dead-ended at its termini. Each of the 30 headers is provided with a suitable flexible connection (not shown) adjacent each of the locomotive stall tracks of the roundhouse. This arrangement permits a fluid connection or a plurality thereof to be made from any locomotive 35 on any of the roundhouse tracks, into any or all of the headers, as may be desired.

The blowoff header or pipe 10 is directly connected, as by a pipe line 16, through a valve 18, to an accumulator tank 20 of substantial size, 50 and pressure resistant; a valved branch pipe 22 also serving to connect the line 16, through a valve 24, to a blowoff water storage tank 26.

The tank 26 is provided internally with a discharge line 28, having its inlet 30 submerged, 55 but kept near the upper surface of the liquid within the tank as by a float 32. The sections of pipe constituting the line 28 are jointedly connected, as through flexible or swing joints 34, a detail of a joint suitable for this purpose being shown in section in Fig. 5.

The line 28 in passing out of tank 26, serves to direct the flow of water into the uppermost pass of a heat exchanger, indicated generally at 36. 60 The details of an exchanger of a suitable type are set forth in my copending application of Serial No. 561,132, filed September 4, 1931, wherein the exchanger is described and claimed. It is thought sufficient for purposes of present description to note that the exchanger 36 comprises a series of convergently and divergently directed trough elements 38, which, however, may be closed completely so as to constitute pipes rather than troughs. The elements 38 thus arranged in zig-zag manner, are closed at their ends by headers

40, extending between and interconnecting which are a plurality of tubes 42 (see Fig. 3). Each of the trough elements is provided with a discharge opening at its lowermost end so that the tubes and headers on the one hand, and the conduits or troughs 38 exteriorly thereof, on the other hand, constitute two complete contiguous circulatory systems operating as a liquid heat exchanging device of countercurrent type. In the system presently illustrated the uppermost 10 element 38 is supplied from the discharge end of the pipe 28, the flow therefrom being crosswise of and from top to bottom of the exchanger. The system of tubes 42 and headers 40 is connected into a fresh water line 44, preferably supplied 15 from a water-softening device of any usual form.

As will appear from Fig. 2, it is my preference to provide the exchanger 36 with a water box 100, shown as disposed at the upper end of the exchanger, and in the inlet portion of the system 20 of troughs 38. The water box 100 may consist of a structure of rectangular transverse section, formed of sheet metal provided with side elements of tapering height, and supported at one end as shown, by a bracket 101, and connected 25 for support at the opposite end to the uppermost header 40. The inlet pipe 28 is preferably directed into one or the high end of the water box 100. The box is provided with a baffle element extending transversely thereof and indicated at 102, the baffle being disposed at an angle say of 30 degrees to the horizontal. The baffle and box serve to reduce the velocity of flow from the pipe 28 and thus tend to promote settling or precipitation 30 of any solids suspended in the inflowing water or 35 other liquid. The box 100 is provided with an outlet or discharge opening 103 closely overlying the upper end of the uppermost trough 38 of the exchanger.

A further improvement in the exchanger 36, 40 over the form in which it is described in my copending application, Serial No. 561,132, above referred to, consists in the addition, within each, or at least certain, of the tube elements of the exchanger, of a spiral thimble structure indicated 45 generally at 104. The location and form of the spiral thimbles best appears in Fig. 2, each thimble consisting of a strip of metal, originally flat in form and of suitable gauge, preferably of a non-corrosive material. Each thimble 104 is 50 formed by twisting such a strip so as to produce thereof a spiral element, the outside dimensions of which correspond substantially to the inside diameter of the tube in which the thimble is disposed. At one, say the uppermost end of the tube 55 in which the thimble is disposed, is provided an L shaped extension 105, the length of this extension so exceeding the diameter of the tube containing the thimble, that the thimble is positioned 60 against displacement resulting from flow of liquid through the tube. The thimble serves to produce a rotary motion of the fluid as it proceeds through the tube, and serves definitely to prevent stratification of the liquid within the tubes. By 65 thus subjecting the liquid content of the tubes to a slow rotary, or perhaps a whirling motion, depending upon velocity, a given length of tubing will serve with greatly increased efficiency as a heat transferring agency.

A convenient mode of installation is to locate the heat exchanger 36 above a washout water storage tank 46. The tank 46 is provided internally with a standpipe or overflow pipe 48, which is by preference readily removable from the tank 75

46 for purposes of cleaning. The inlet to pipe 49 is kept appreciably above the bottom of the tank, so that the lowermost portion of the tank may provide a trap or reservoir for scale and foreign 5 matter which may precipitate in the tank 46, the capacity of which is such as to require removal of accumulated solids only at wide intervals.

Connected into the upper portion of tank 46, is an intake pipe 50 directed to a pump 52 discharging into a pipe line 54 directed into the washout header 12. The pump 52 may be of any suitable type, but my preference is to utilize a centrifugal or other revolving impeller type pump at this point in the system, steam pumps of usual reciprocating type having been found inferior thereto in actual practice. The tank 46 is conveniently disposed as shown by Fig. 1, partly below the ground line or floor level, and with the stand-pipe or overflow 48 somewhat above the intake 20 to pump 52, obviating any difficulty of maintaining the pump 52 in prime.

As a storage reservoir for fresh boiler fillup water, there is provided a tank 56, disposed above and communicating with which is a water heater 25 head of steam-contact type, the head being indicated generally at 58 (Fig. 1), and shown in detail in Fig. 4. The construction and arrangement of parts in this device are fully described in Letters Patent No. 1,879,582, issued to this applicant under date of September 27, 1932. Briefly described, this device consists of a casing 60 of open end, flattened cylindrical form, provided with tangentially arranged, opposed steam inlet openings 62. Branch pipes 64 serve, together with a steam line 66, to direct flash steam from the blow-off storage tank 26, to points peripherally and internally of the casing 60. Disposed centrally of the casing 60 is a cluster fitting 68, providing two separate sets of water inlet nozzles 70 and 72. 30 A connection 74 is provided from the upper set of nozzles 72, to the header 14, for a purpose hereinafter appearing. The lower set of nozzles 70 is supplied from a water line 76, directed from the uppermost header 40, and hence from the inner 35 or tube circuit of the heat exchanger. The arrangement of the heater head is such that, as a water supply from either or both of the pipe lines 76 and 14 is sprayed upwardly through the steam zone it hits the top of casing 60 and falls 40 back through the same steam zone and out the bottom of casing 60 into fresh fillup tank 56. Flash steam entering through the tangential openings 62 gives up its heat content or a substantial part thereof, to the incoming water, 45 which immediately descends by gravity, through the lower open end of the heater head 58, and thus into the fresh feed water storage tank 56. Water to be utilized for boiler refilling purposes is withdrawn from the tank 56 as through a 50 jointed line 78 provided with flexible joints 34 which may be similar to the swing joints in the line 28. As in the blowoff water storage tank 26, the inlet to line 78 is kept submerged, and spaced slightly from the top of the water level in tank 56, as by a float 80, to secure the hottest and cleanest water available. The line 78 is directed 55 outwardly through the wall of tank 56, thence to the inlet of a centrifugal pump, or other suitable displacement means, indicated at 82. The outlet from pump 82 is connected as by a line 84, through a steam ejector 86, thence into the feed water header 14. The fitting 86 consists of an 60 ejector nozzle, provided preferably with a T-shaped body, the lateral branch of which is connected as through a valve 88 into the upper por-

tion of the accumulator tank 20, for a purpose more fully hereinafter appearing. A check valve 89 is also desirably disposed between the accumulator 5 20 and the valve 88.

The details of structure and the internal arrangement of parts of a presently preferred form of ejector such as 86, best appear in Fig. 6, wherein the fresh water pipe 84 is shown as connected by a flange joint 106 to the body 107 of the structure. A connection is made at the bottom 10 of the body 107, as by a vertical pipe portion 108, into the accumulator 20. The parts internally of the ejector device, include a threaded 15 sleeve member 109, in which is mounted a tapered plug element 110, terminating in a flared, stream-forming portion 111 located somewhat beyond the center of a Venturi fitting 112. The inner end of the venturi is open 20 to permit the entrance of steam from the chamber within the body, steam being supplied there- 25 to through the pipe 108 from the accumulator. An auxiliary fitting 113 forms a prolongation of the Venturi element 112, the members 112 and 113 being telescopically connected and detachably carried by the body as by threaded cap screws 114. At the outer end of the extension 113 is connected a pipe 115, directed into the header 14 above described.

In operation, as the fresh water is introduced under pressure to the sleeve 109, the augmented 30 velocity due to the throat portion of the Venturi elements, creates a suction within the inlet end of the Venturi fitting 112 which is open to receive the steam from the accumulator 20. The steam-receiving portions of the structure are thus sub- 35 jected to a somewhat reduced pressure or suction, with the effect that the fresh water becomes mixed with the flash steam from the accumulator 20, and serves to heat the fresh water before introduction thereof to the header 14. The type 40 of steam ejector here described, is available to the trade for numerous other uses, and does not, of itself, constitute a part of the present invention. Hence, no claim is made to the device except in combination with other items of apparatus herein described.

It will be understood that other valves may be interposed in the several headers, water lines and steam lines, at desired locations; it is my preference, for example, to locate a valve 90 in a 50 line 92, the latter line of pipe connecting the feed water header 14 with one or the upper set of the water nozzles in the heater head 58.

Since the liquid in tank 46 sometimes contains a considerable amount of foreign matter or sludge 55 in suspension, it is my preference to provide the inlet to the pump 52 with a strainer or the like, which will prevent the entrance of solids to the pump and to the line into the header 12. For this purpose I have devised a strainer shown in 60 preferred form in Figs. 7 and 8. This structure may be supported within the tank 46 as by a suitable bracket 120 carried by a wall of the tank. The strainer proper consists of a base plate 121 which may be bolted or otherwise affixed 65 to the bracket 120. The plate 121 is provided with recesses, say of circular section, to receive in spaced relation a plurality of vertically disposed pins or rods 122. These rods are, in the example shown, arranged in the form of a square, 70 with the rods so spaced as to restrict the size of solid particles which may pass therebetween. The relation of the external diameter of pins 122 and the recesses therefor in the base plate 121 is such that the pins may be driven into the re- 75

cesses, and thus engaging them with a driving fit; the pins are rigidly held in assembled relation.

Depending upon the depth or height of the strainer assembly, it may be also desirable to tie the pins in assembly at their upper or outer ends. This is accomplished, according to Fig. 7, by welding frame elements of strap material 123 to the inner sides of the upper or outer ends of the pins, thereby leaving the exterior surfaces of the pins completely unobstructed throughout their entire exposed length.

The intake fitting for the pump 52 is shown at 124 as consisting of an elbow turned so as to present its opening parallel to the plate 121, and spaced thereabove. The elbow is carried by the intake pipe 125 connected to the pump 52.

An advantage of the present structure is found in the ease of cleaning the strainer of accumulated solids. It will appear that the water has access to the intake from all sides of the pin-screen structure, and hence any entrained or occluded solids will be trapped against the exterior surfaces of the pins. After a period of use, or when the accumulation of solids necessitates their removal, an ordinary garden rake may be employed, and the foreign material removed from along the pins either by direct lateral disengagement of the material, or by raking it upward along the pins and away from the tops thereof. The latter practice has been found particularly advantageous where the entrained or filtered material consists of fibrous or like substances, it being understood that the described pin-type strainer may be advantageously utilized at other points in the present system, or in connection with pumps or pipe lines handling a great variety of solid-containing liquids, and employed with other apparatus.

It will be understood that the foregoing description of parts intentionally omits certain details of structure of lesser importance and which will suggest themselves to those skilled in the art. For example, such of the piping as desired, and certain items of equipment employed for storage or heat exchanging purposes, may be heat insulated. Sludge drains (not shown) may also be provided in the tanks 20, 26, and 56. Obviously also the space relation prevailing between the different items of apparatus as depicted in Fig. 1, is not necessarily adhered to in practice. The arrangement of parts may obviously be employed in accordance with the space conditions prevailing in a particular roundhouse, or a stationary boiler installation.

According to the practice of the present invention, when a locomotive is brought into the roundhouse, containing, say 3000 gallons of water at say 360° F., or 150 pounds steam pressure, the locomotive is connected into the blow out header 10, valves 24 and 88 are closed, and valve 18 opened, so that a part of the blowoff water and steam are discharged into the accumulator 20. The accumulator is so proportioned that it will accommodate enough concentrate to secure a favorable heat balance, at a pressure say of 40 pounds. The remainder of the boiler water with its corresponding heat content, at this time remains in the locomotive. Valve 18 is now closed so that the necessary heat is held in the accumulator 20, at a gauge pressure, say of 40 pounds, corresponding to 287° F. Valve 24 is then opened, so as to connect the header 10, through line 22, with the blowoff water storage tank 26, and the remainder of the locomotive sludge

water at say 40 pounds pressure, is conducted into the tank 26. The substantial amount of flash steam which results from the entrance of the blowoff water into tank 26, is conducted through line 66 and thence into the tangential steam openings 62 of the heater head 58. During this time fresh water, say at 40°-80° F., proceeding from the softener or other supply, is being conducted through the line 44, thence through the tube and header system of the exchanger 36, thence outwardly through the pipe line 76 to one or other lower set of the nozzles, such as 78, of the heater head 58. It will appear that the water in line 76, prior to its entrance to the heater head, will have been heated substantially by conduction in the exchanger, due to the countercurrent flow of hot water from the tank 26.

Water from the nozzles 76 and/or 72 of the heater head, is brought into contact with the whirling jets of flash steam, which augment the heat content of the fresh water supply, the steam-treated water being delivered by gravity into the fresh water tank 56, at a temperature of the order of 140-180 degrees F.

As the blowoff water from tank 26 is conducted through the line 28, and thence into the heat exchanger 36, preferably the outer elements or circuit thereof, the blowoff water is cooled to a temperature of 130 degrees F. or lower, this cooling operation, as will have been observed, serving to heat up the incoming fresh water in conduits 44, 48, and 42, enroute to the heater head. This cooled blowoff water may be delivered by gravity from the exchanger 36, directly into the washout water storage tank 46 where it is available through pump 50, line 54 and the washout header 12, for purposes of cleaning the locomotive, interiorly and exteriorly. At this temperature the water may be safely handled through a hose or other flexible conduit for washing purposes. As will have appeared from the description of structure, the overflow pipe 48 from the washout storage tank 46, serves automatically to remove any blowoff water in excess of actual requirements for washing purposes.

Since a substantial cooling of the blowoff-washing water occurs in the exchanger, a substantial precipitation of mineral content will take place in the tank 46, which thus serves as a settling basin. The location of pipes 48 and 50 above the bottom of the tank, permits a periodic removal of sludge or precipitate, and entraps these solid materials, preventing any further circulation thereof through the system.

After thorough cleaning of the locomotive by means of the wash water from the tank 46, fresh feed water for refilling the boiler is pumped from the storage tank through line 78, pump 82 and line 84 into the feed water header 14, thence to the locomotive boiler. It will be seen that in traversing this line, water from tank 56 proceeds through the steam ejector 86, a steam connection being made thereto from the accumulator by opening the valve 88. Flash steam from the accumulator at about 40 pounds pressure immediately mixes with the fresh feed water in the inductor, en route to the locomotive boiler. This permits carrying a pressure in the feed water line, and results in the introduction of the fresh refill water at a temperature substantially above the boiling point, say in the range of 220 to 250 degrees F., and at a pressure considerably above atmospheric. A corresponding heat con-

tent of the accumulator fluid, is thus delivered to the locomotive.

By thus filling the locomotive boiler with water at a temperature say of the order of 250 degrees F., instead of at the prevailing temperature, under the older practice, of 180 degrees F., the steaming-up time heretofore required, is considerably reduced, as is the amount of fuel required to raise the boiler to a steaming condition.

10 It will have been observed from the foregoing that a distinct saving is effected in roundhouse practice, in that, without any extraneous source of heat, a locomotive boiler after cleaning and refilling, possesses a heat content prior to re- 15 steaming represented by, say 3500 gallons of water at a temperature of 220 to 250 degrees F.; under the older practice, due to undue waste and failure properly to reclaim the heat content of blowoff water, the same amount, say of 3500 gallons of water, existed prior to re-steaming, at a 20 temperature of not to exceed 180 degrees F.

It will also have been observed from the foregoing description that no extraneous source of heat need be employed to obtain the higher temperature of the incoming boiler feed water. The relatively larger amount of reclaimed heat is due in part to the confinement and maintenance of the greater part of the original steam pressure, whereby there is conserved a substantial part of 30 the latent heat of vaporization. A major factor in heat conservation consists in confining the flash steam within the sludge body with little loss, entirely within a closed system, at a pressure above atmospheric. The heat saving incident to 35 the present method and apparatus, is also traceable in large measure to the use of the very efficient counterflow heat exchanging device 36. The necessary reduction of temperature of a certain amount of the water for purposes of washing, is 40 accomplished in the exchanger without any material waste of heat; this heat being utilized in, and imparted to the fresh water or boiler feed supply in the tank 56. The use of a steam and water contact device, such as the heater head 58 45 of the present example, also serves much more efficiently than under prevailing practices, to transfer the heat content of the flash steam from tank 26, to the fresh water supply utilized for refill.

50 While the description has been particularized with respect to a method and apparatus for reclaiming the heat of locomotive boiler fluids, the principles of the present invention are applicable equally, with or without minor changes, to 55 stationary steam boilers, heating plants utilizing steam, steam generators, and other analogous equipment. The present detailed description of an illustrative embodiment of the invention should not be understood in a limiting sense, since 60 numerous changes may be made in the parts, their combinations, and the practices employed in connection therewith, without departing from the full intended scope of the invention as defined by the appended claims.

65 I claim:

1. The herein described method of reclaiming heat from a steam boiler incident to blowoff and replacement of the boiler water supply, which consists in heating the supply water in three 70 stages, namely, first by circulation countercurrently to a flow of the blowoff water, secondly by admixing a stream of fresh supply water, and a flow of flash steam from the blowoff water, and thereafter injecting steam, at a higher pressure than said flash steam, into the supply water 75

and in introducing the heated supply water to the boiler.

2. The herein described method of reclaiming heat from a steam boiler, incident to replacement of the boiler water supply, which consists in 5 blowing off the boiler while under a relatively high pressure, into a steam-water container, and at a relatively low pressure in a second such container, in preheating fresh water by water from the second container, and in turbulently admixing streams of preheated fresh supply water and flash steam from the said second blowoff water container, out of contact with the body of blowoff water therein, in injecting steam from the high pressure container to the supply water, and 10 in adding the steam-treated supply water to the boiler for refill purposes. 15

3. The herein described method of reclaiming heat from a steam boiler as an incident to boiler washing and replacement of the boiler water supply, which consists in conducting portions of the blowoff water into separate high and low pressure containers therefor, in cooling a portion of the blowoff water from the low pressure container by conduction of its heat content to a stream of 20 fresh boiler feed water, in conducting the cooled blowoff water to a reservoir therefor to effect precipitation of a portion of the mineral content of the blowoff water, and thereafter utilizing the water from such reservoir for boiler washing purposes, in utilizing the steam from the low pressure container for a second stage of heating of the feed water, and thereafter utilizing the steam from the high pressure container as a third stage 25 of heating the feed water. 30

4. The herein described method of reclaiming heat from a steam boiler, incident to washing the boiler and replacement of its water supply, which consists in conducting relatively high and low temperature portions of the boiler blowoff fluid to 40 separate containers therefor, in utilizing a relatively low temperature portion of such blowoff fluid for boiler washing purposes, in concurrently heating the feed water and cooling the wash fluid, by countercurrent circulation thereof through adjacent heat transferring passages, in further heating the feed water from the relatively low temperature fluid, and thereafter in a separate stage, by contact with the high temperature fluid. 45

5. The herein described method of reclaiming heat from a steam boiler incident to replacement of the boiler water supply, which consists in segregating and separately confining quantities of the boiler blowoff water and steam, as high and low temperature portions respectively, in utilizing 55 the lower temperature portion of the blowoff fluid for heating, by conduction, a supply of fresh feed water, in further heating the feed water by admixture thereof with flash steam from the said lower temperature portion of blowoff water and 60 in still further heating the feed water by absorption of the heat content of the high temperature portion incident to circulation for refill purposes. 65

6. The herein described method of reclaiming heat from a steam boiler as an incident to replacement of the boiler water supply, which consists in storing under pressure exteriorly of the boiler a substantial part of the boiler blowoff water, storing in a second container an additional portion of the blowoff water, in concurrently circulating in separate systems a stream of water from said second blowoff container and a stream of 70 fresh feed water, in subjecting said stream of fresh feed water to a turbulent admixture with flash steam from said second blowoff container, 75

and in thereafter subjecting the supply of fresh water to a flow of steam from the confined blow-off water, and introducing the supply of steam-treated fresh water to the boiler, under a substantial steam pressure.

7. In apparatus for reclaiming the heat of drained boiler fluid, a boiler drain conduit, a tank structure for confining blowoff water and steam under pressure, a connection between said tank structure and said conduit, a fresh feed water conduit, means for preheating the fresh feed water in said conduit, including elements for separately and countercurrently circulating in adjacency thereto a portion of the blowoff water, a storage tank for the preheated feed water, an injector having a steam connection to said blow-off pressure tank structure, a water inlet connection to said preheated feed water storage tank, and a discharge conduit for directing the steam treated feed water from the injector to the boiler, for refill purposes.

8. Apparatus for reclaiming heat from drained boiler fluids, including a low pressure container and a high pressure container, each for blowoff water and steam, a conduit for fresh feed water, means for circulating the water from said low pressure blowoff container countercurrently and adjacently in heating relation to the flow of fresh feed water in said conduit, means for effecting a further heating stage of the feed water by contact with steam from the low pressure blowoff container, a conduit arranged for directing the steam heated feed water, for boiler refill purposes, and means in said conduit for utilizing the heat content of the high pressure container in a subsequent heating stage as the feed water is utilized for refill purposes.

9. Apparatus for reclaiming heat from drained boiler fluids, including a container for receiving blowoff water and steam under pressure, a fresh water conduit for boiler refill purposes, a conduit for separately but adjacently circulating blowoff water countercurrently to the fresh water for pre-heating the fresh boiler feed water while traversing its said conduit, a storage tank for the pre-heated feed water, a heater of steam-water contact type connected for utilizing a portion of the blowoff steam for heating feed water prior to its introduction to the storage tank, and a steam ejector having its steam supply connected to said blowoff container and being connected in the fresh water conduit beyond the storage tank, and adapted for the introduction of fresh water to the boiler, under substantial steam pressure.

10. Apparatus for reclaiming heat from drained boiler fluid, including a pressure container for receiving blowoff water and steam and confining same in three fractions, at low, intermediate and high temperature, after their removal from the boiler, a fresh water supply line, means connected into the blowoff container and fresh water line for adjacently circulating separate streams of water therefrom for heating the fresh water supply, by utilization of the low temperature fraction, means for further heating the fresh water supply in a second stage by contact with the intermediate fraction of fluid from said blowoff container, means for conducting the fresh water from the last said heating means to

the boiler, for refill purposes and a heat transfer device associated with the said conducting means, said device utilizing the said high temperature fraction as a final heating stage incident to refill.

11. Apparatus for reclaiming heat from boiler blowoff fluids, including a blowoff pressure container, a pressure tank forming a reservoir for blowoff water, the container and reservoir being provided with steam spaces, valved conduits from the boiler to said container and reservoir, a fresh water supply conduit, a heat exchanger having separate circulatory systems connected respectively to said blowoff reservoir and to said supply conduit, a water heater of steam-water contact type, having a steam connection to the steam space of said blowoff reservoir and a water connection from said heat exchanger, a fresh water storage tank communicating with the contact type heater, and connections for supplying the storage tank therefrom, a steam ejector connected to the steam space of said blowoff pressure container, a conduit from the fresh water storage tank to said ejector, a pump in the last said conduit, and a conduit from said ejector to the boiler, for refill purposes.

12. Apparatus for reclaiming heat from boiler blowoff fluids, including a blowoff header, adapted to be connected to the boiler to be drained, a wash out header adapted to be connected to the boiler for washing purposes, a feed water header adapted for the supply of fresh water to a boiler after draining and cleaning thereof, a pipe line from said blowoff header, provided with two branches, valves in said branches, a pressure accumulator for blowoff water and steam, adapted to contain a substantial portion of the blowoff water from the boiler under treatment, said accumulator being connected to one of the branches of said blowoff pipe, a storage tank for the remaining blowoff water, connected to the other of said branches, the pressure accumulator and storage tank each being closed and having a steam space in its upper portion, a heat exchanger of countercurrent type, characterized by an outer circuit and an inner circuit, the outer circuit of the exchanger being connected to the water-containing part of said blowoff water storage tank, a fresh water supply conduit connected to the inner circuit of the exchanger, a water heater of steam-water contact type, a water connection to said heater from the inner circuit of said heat exchanger, a steam connection to said heater from the steam space of the blowoff water storage tank, a fresh water storage tank and a fresh water connection therefrom to said heater, means including a pump connecting the fresh water storage tank to the feed water header, a settling reservoir for blowoff water, having a supply connection to the outer circuit of said heat exchanger, means including a pump for delivering water under pressure from said settling reservoir into the washout header, for boiler washing purposes, and a steam ejector, having a steam connection with the steam space of the blowoff pressure accumulator and connected with the fresh water storage tank through the pump and associated means first aforesaid, the ejector being further provided with an outlet connection to the first said feed water header.
